CLAES F. ROBERG AND AUGUST A. MALMBERG, OF CHICAGO, ILLINOIS.

IRONING-MACHINE.

1,105,207.

Specification of Letters Patent. Patented July 28, 1914.

Application filed February 12, 1913. Serial No. 747,891.

To all whom it may concern:

Be it known that we, CLAES F. ROBERG and AUGUST A. MALMBERG, citizens of the United States, and residents of the city of Chicago, county of Cook, and State of Illinois, have invented certain new and useful Improvements in Ironing-Machines, of which the following is a specification.

Our invention relates to improvements in ironing machines and has for its object the production of a device of this character which will be especially adapted for home use or in private laundries.

A further object of our invention is the production of a machine of the character mentioned which will be of durable and economical construction and efficient in use.

Other objects will appear hereinafter.

With these objects in view, our invention consists in the combinations and arrangements of parts all as will be hereinafter described and claimed.

Our invention will be best understood by reference to the accompanying drawings forming a part of this specification, and in which,

Figure 1 is a partial sectional side elevation of an ironing machine embodying our invention, Fig. 2 is a partial sectional side elevation of one of the levers whereby the ironing rollers may be moved outwardly through foot power, Fig. 3 is a front elevation of the upper end portion of the lever shown in Fig. 2, Fig. 4 is a front elevation of the ironing machine, the central portion thereof being broken out and one of the ironing rollers being omitted as well as the springs and spring housings coöperating therewith in order to better illustrate the construction, Fig. 5 is a top plan view of the construction shown in Fig. 4, the hand screws coöperating with the ironing roller springs being shown in section, Fig. 6 is a side elevation of the segmental ironing member of the ironing machine detached, the central portion thereof being broken out, Fig. 7 is an end elevation of said ironing member, and Figs. 8 and 9 are a front view and side elevation respectively of one of the supporting members coöperating with said segmental ironing member.

The preferred form of construction, as illustrated in the drawings comprises a frame consisting of two spaced members 1 which are rigidly connected by bars 2. Ar-

ranged between the upper ends of the frame members 1 is a segmental ironing member 3 the respective ends of which are secured to supporting members 4. The attachment of said ironing member to the supporting members 4 is effected by means of screws the inner ends or heads of which engage slotted lugs 5 provided at the open ends of said ironing member. The supporting members 4 are fulcrumed at 4' to the frame members 1 so as to permit of oscillatory movement of said ironing member 3. The center of curvature of the convex side of the ironing member 3 is coincident with the center of oscillation of said ironing member and said surface is smooth and polished so as to permit of the ready sliding thereover of the articles ironed.

The ironing member 3 is heated during operation of the ironing machine by means of a gas pipe 6 which is arranged therein, the upper side of said pipe being perforated for the escape of gas. The end pieces 4 are provided with elongated arcual slots 7 to accommodate the ends of pipe 6 in order to permit of rocking movement of the ironing member 3, the ends of said pipe being rigidly secured in the frame members 1. One end of the pipe 6 is connected with any suitable source of fuel supply, a suitable valve 8 being provided for governing the flow of gas to said pipe. The ironing member 3 is normally held at one terminal of its rocking movement against stops 9 which are formed at the inner sides of the frame members 2 by means of a helical tension spring 10, stops 9' serving to limit the rocking movement of said ironing member downwardly. The stops 9' are formed at the inner sides of arms 12 which are arranged at the inner sides of the frame members 1 between the latter and the respective ends of the ironing member 3, the lower ends of said arms 12 being fulcrumed at 13 to said frame members 1. Arranged between the upper ends of the arms 12 are the padded ironing rollers 14 of the ironing machine, said rollers when the device is in use rotating in contact with the convex side of the ironing member 3, the amplitude of oscillation of said ironing member being such that the same is constantly in registration with said rollers. The journals 15 of the rollers 14 are mounted in bearing blocks 16 which are slidably mounted in radially disposed slots 17.

formed at the upper or free ends of the arms 12. Helical compression springs 18 coöperate with the bearing blocks 16 for normally holding the rollers 14 in contact with the ironing member 3. Housings 19 arranged at the outer ends of the slots 17 inclose the outer ends of the springs 18. Hand screws 20 are threaded in the outer ends of the housings 19 for coöperation with the springs 18 to regulate the tension of said springs as exerted upon the bearing block 16.

Pivotaly mounted at the upper ends of the arms 12 are arms 21 which are provided at their lower ends with hooks 22 adapted 15 to engage under lugs 23 formed at the inner sides of the frame members 1 to releasably lock the arms 12 against rocking movement and hence to hold the rollers 14 in contact with the ironing member 3. The upper ends 20 of the arms 21 are connected by means of a bar 24 which serves in the capacity of a handle adapted for engagement during operation of the machine to effect oscillation of the locking members 21 in locking or unlock- 25 ing the arms 12 carrying the rollers 14. A rod 25 rigidly connects the upper ends of the arms 12 in order to insure unisonous movement of said arms.

Fulcrumed upon the respective ends of the 30 rod 25 adjacent the inner sides of the mem- bers 21 are arms 26 the lower ends 27 of which are pivotally connected with the upper ends of links 28, the lower ends of said links being pivoted at 29 to the frame mem- 35 bers 1. With this arrangement, it will be seen, that a toggle will be constituted by each pair of coöoperating members 27 and 28 and so that when the upper ends of the arms 26 are rocked, said toggles will be ac- 40 tuated to cause rocking of the arms 12 and hence movement of the rollers 14 into or out of engagement with the ironing member 3. Inwardly projecting from the arms 21 are pins 30 which engage arcual elongated slots 45 31 formed in the upper ends of the arms 26. With this arrangement, it will be seen, that an operative connection is established be- 50 tween the arms 21 and 26 and so that in operation, upon forward oscillation of the arms 21, the lower hooked ends 22 thereof will first be moved to inoperative position to release the arms 12 whereupon oscillatory movement will be imparted to the arms 26 to cause straightening of the toggles consti- 55 tuted by the portions 27 and 28 and thereby effect rocking of the arms 12 to carry the rollers 14 out of engagement with the ironing member 3. By the employment of the slot-and-pin connection between the arms 21 and 26, during oscillation of the arms 21 the oscillatory movement which is imparted to the arms 26 by said arms 21, is delayed until the lower hooked ends 22 of the arms 21 have disengaged the lugs 23. With this con- 60 struction the unlocking and movement of

the padded rollers of the ironing machine out of engagement with the heated ironing member may be effected with ease and ex- 70 pedition and so that in the operation of the ironing machine, upon cessation of opera- 75 tion, said padded rollers may be readily and quickly moved to inoperative position to prevent scorching or burning of the padding of said rollers which otherwise results if permitted to remain in contact with the 75 heated ironing member.

Fulcrumed at 32 upon the inner sides of the frame members 1 are levers 33 pro- 80 vided at their upper ends with lugs 34 to which are secured curved bars 35. The bars 35 are adapted to contact with lugs 36 which are formed at the under sides of the bearing blocks 16, the arrangement being such, that, when the lower ends of levers 33 are rocked forwardly, the bars 35 will be moved up- 85 wardly to cause movement of the rollers 14 out of contact with the ironing member 3. The lower ends of the levers 33 are connect- 90 ed by a cross piece 37 which is provided at its front edge with a medially positioned 90 tongue 38 adapted to be engaged by the foot in order to cause operative rocking of the levers 33. One of the bars 2 of the frame of the mangle is positioned in close prox- 95 imity with the bar 37, so as to serve as a 95 stop for the foot to determine the amplitude of operative movement of said bar 37 and hence rocking movement of the levers 33. The last described construction for effecting 100 outward movement of the rollers 34 is de- 100 signed for employment where the article, which it is desired to iron, is of considerable thickness. In these cases it is difficult to start the article into the machine between the first roller 14 and the ironing member 105 3, and in order to facilitate this starting, during operation of the ironing machine, the levers 33 are operated by means of the foot pressing upon the tongue 38 to move the rollers 14 outwardly to a limited extent. 110 For ordinary ironing, that is where the arti- 110 cles are not of great thickness, this mecha- nism for moving the rollers outwardly will not be utilized.

The oscillatory mounting of the ironing 115 member 3 is also to facilitate the starting of the articles to be ironed into the machine. By rockingly mounting the member 3 as mentioned, the latter, in starting an article through the ironing machine, will operate 120 in the same manner as a roller relative to the first roller 14, rocking simultaneously with said roller to a limited extent in the starting of the article into the machine. The difficulty experienced in starting an 125 article through the machine is occasioned by reason of the fact that ordinarily the edge of an article is hemmed or double and therefore the end of the article is of greater thickness than the central portion thereof. 130

Therefore in ironing an article, the greatest pressure will be exerted at the start, but this pressure will be relieved as the thinner central portion of the article is reached and so that in the operation of the machine the pressure upon the ironing member 3 will be reduced, after the article has been started into the machine so as to permit of said ironing member being rocked to its normal 10 position under the influence of spring 10.

The articles which it is desired to iron are first arranged upon the table 39 provided at the front side of the machine, the upper side of said table being in substantially the 15 same plane as the upper end of the ironing member 3. A transversely extending rod 39' extends between the upper ends of the arms 12 in close proximity with the upper end of the ironing member 3 to serve as a 20 guard to prevent the fingers from being inserted between the first roller 14 and the ironing member 3.

In the operation of the machine, the rollers 14 are continuously rotated through the 25 medium of gears 40 provided at corresponding ends of the journals 15 of said rollers, said gears meshing with an idler gear 41 mounted upon a stub shaft 41'. The gear 41 meshes with a pinion 42 mounted upon 30 a stub shaft 43. A worm wheel 44 connected with the pinion 42 meshes with a worm 45 which is carried by the shaft 46 which is mounted in bearings 47 secured upon the outer side of one of the frame members 1. 35 At one end of the shaft 46 is provided a channel pulley 48 through the medium of which power may be applied in order to drive the ironing machine as will be readily understood.

40 An ironing machine of the construction set forth is of simple and economical construction hence may be manufactured at a comparatively low cost and the same will be found of high efficiency in operation.

45 While we have illustrated and described the preferred form of construction for carrying our invention into effect, this is capable of variation and modification without departing from the spirit of the invention.

50 We, therefore, do not wish to be limited to the precise details of construction set forth, but desire to avail ourselves of such variations and modifications as come within the scope of the appended claims.

55 Having described our invention what we claim as new and desire to secure by Letters Patent is:

1. In an ironing machine, the combination 60 of an ironing member having a smooth convex side; a plurality of rollers adapted to rotate in contact with said side of said member; oscillatory arms carrying said rollers; means cooperating with said arms for releasably holding said rollers in operative 65 relation with said ironing member; and tog-

gles for moving said rollers out of contact with said ironing member, substantially as described.

2. In an ironing machine, the combination 70 of an ironing member having a smooth convex side; a plurality of rollers adapted to rotate in contact with said side of said ironing member; oscillatory arms carrying said rollers; means for releasably holding said rollers in operative relation with said ironing member; and toggles for moving said rollers out of contact with said side of said ironing member, substantially as described. 75

3. In an ironing machine the combination 80 of an oscillatory ironing member having a smooth convex side, the center of curvature of said side being coincident with the center of oscillation of said member; a plurality of rollers adapted to rotate in contact with said side of said ironing member, said ironing member remaining constantly in registration with said rollers; means for releasably holding said rollers in contact with said side of said ironing member; and means 85 for moving said rollers out of contact with said ironing member, substantially as described. 90

4. In an ironing machine, the combination 95 of an oscillatory ironing member having a smooth convex side, the center of curvature of said side being coincident with the center of oscillation of said member; means for yieldingly holding said ironing member at one of its terminals of oscillation; a roller adapted to rotate in contact with said side of said ironing member; and means for releasably holding said roller in contact with said side of said ironing member, substantially 100 as described. 105

5. In an ironing machine the combination 110 of an oscillatory hollow ironing member having a smooth convex side; a heating element arranged within said ironing member, the ends of said ironing member being slotted to accommodate said heating element and to permit of oscillation of said ironing member; means for yieldingly holding said ironing member at one of its terminals of oscillation; a roller adapted to rotate in contact with said side of said ironing member; and means for yieldingly holding said roller in contact with said ironing member, substantially as described. 115

6. In an ironing machine, the combination 120 of an ironing member; a plurality of rollers adapted to rotate in contact with said ironing member; means for yieldingly holding said rollers in operative relation with said ironing member; means for simultaneously moving said rollers out of contact with said ironing member, said means comprising oscillatory levers; and bars carried by said levers adapted to engage under the respective extremities of said rollers 125 130

whereby, when said levers are oscillated, said bars will move said rollers outwardly, substantially as described.

7. In an ironing machine, the combination of an ironing member; a plurality of rollers adapted to rotate in contact with said ironing member; means for yieldingly holding said rollers in operative relation with said ironing member; means for simultaneously moving said rollers out of contact with said ironing member, said means comprising oscillatory levers arranged at the respective ends of the machine; and a bar carried by each of said levers adapted 10 to engage under all of the ends of the rollers at the corresponding end of the machine whereby, when said levers are oscillated, said bar will move said rollers outwardly, substantially as described.
8. In an ironing machine, the combination of an ironing member; a plurality of rollers adapted to rotate in contact with said ironing member; means for yieldingly holding said rollers in operative relation 15 with said ironing member; means for simultaneously moving said rollers out of contact with said ironing member, said means comprising a bar arranged at each end of the machine adapted to engage under all 20 of the corresponding ends of said rollers whereby, when said bars are moved outwardly, said rollers will be moved from engagement with said ironing member; and means for manually actuating said bars, 25 substantially as described.

9. In an ironing machine, the combination of an ironing member; a plurality of rollers adapted to rotate in contact with said ironing member; movable supporting 30 members in which the bearings of the respective extremities of said rollers are movably mounted; means for releasably locking said supporting members with said rollers in contact with said ironing member; 35 means for moving said supporting members, after release thereof, to move said rollers out of contact with said ironing member; and means for moving said rollers relative to said supporting members out of 40 contact with said ironing member, while said supporting members are locked in operative positions, substantially as described.

10. In an ironing machine, the combination of an ironing member; a plurality of 45 rollers adapted to rotate in contact with said ironing member; oscillatory supporting members in which the bearings of the respective ends of said rollers are movably mounted; means for releasably locking said 50 supporting members with said rollers in contact with said ironing member; means for rocking said supporting members, after release thereof, to move said rollers out of contact with said supporting members; and means for moving said rollers relative to 55

said supporting members out of contact with said ironing member, while said supporting members are locked in operative positions, substantially as described.

11. In an ironing machine, the combination of an ironing member; a plurality of rollers adapted to rotate in contact with said ironing member; movable supporting members carrying said rollers; means for releasably locking said members with said 70 rollers contacting with said ironing member; means for moving said supporting members to move said rollers out of contact with said ironing member; and an operative connection between said locking 75 means and said last mentioned moving means whereby, upon actuation of said locking means to unlock said supporting members, the latter will be moved to inoperative position, substantially as described.

12. In an ironing machine, the combination of an ironing member; a plurality of rollers adapted to rotate in contact with said ironing member; movable supporting 90 members carrying said rollers; means carried by said supporting members for releasably locking said supporting members with said rollers contacting with said ironing member; means for moving said supporting member to move said rollers out of contact with said ironing member; and an operative connection between said locking 95 means and said last mentioned moving means whereby, upon actuation of said locking means to unlock said supporting members, the latter will be moved to inoperative 100 position, substantially as described.

13. In an ironing machine, the combination of an ironing member; a plurality of 105 rollers adapted to rotate in contact with said ironing member; oscillatory arms carrying said rollers; oscillatory locking means for releasably locking said arms with said rollers contacting with said ironing member; means for rocking said arms to move said rollers out of contact with said ironing member; and an operative connection between said locking 110 means and said last mentioned rocking means whereby, upon oscillation of said locking means to unlock said arms, said arms will be rocked to inoperative 115 position, substantially as described.

14. In an ironing machine, the combination of an ironing member; a plurality of 120 rollers adapted to rotate in contact with said ironing member; oscillatory arms carrying said rollers; oscillatory locking means carried by said arms for releasably locking said arms with said rollers contacting with said ironing member; means for rocking said arms to move said rollers out of contact with said ironing member; and an operative connection between said locking 125 means 130

means and said last mentioned rocking means whereby upon oscillation of said locking means to unlock said arms, said arms will be rocked to inoperative position, substantially as described.

15. In an ironing machine, the combination of an ironing member; a plurality of rollers adapted to rotate in contact with said ironing member; oscillatory arms carrying said rollers; oscillatory locking means carried by said arms for releasably locking said arms with said rollers contacting with said ironing member; toggles for rocking said arms to move said rollers out of contact with said ironing member; and a slot-and-pin connection between said locking means and said toggles whereby upon unlocking of said arms through rocking of said locking means, said toggles will be operated to rock said arms outwardly, substantially as described.

16. In an ironing machine, the combination of an ironing member; a plurality of

rollers adapted to rotate in contact with said ironing member; oscillatory arms carrying said rollers; oscillatory locking means carried by said arms for releasably locking said arms with said rollers contacting with said ironing member; toggles for rocking said arms to move said rollers out of contact with said ironing member; and a slot-and-pin connection between said locking means and said toggles whereby upon unlocking of said arms through oscillation of said locking means, said toggles will be operated to rock said arms to inoperative position, substantially as described.

In testimony whereof we have signed our names to this specification in the presence of two subscribing witnesses.
